United States Patent Office.

EDWIN CHAPMAN AND CHARLES T. ALLAIRE, OF ROCHESTER, MINNESOTA.

Letters Patent No. 73,780, dated January 28, 1868.

IMPROVEMENT IN STEAM-GENERATORS.

The Schedule referred to in these Letters Patent and making part of the same.

TO ALL WHOM IT MAY CONCERN:

Be it known that we, EDWIN CHAPMAN and CHARLES T. ALLAIRE, of Rochester, in the county of Olmsted, and State of Minnesota, have invented a new and useful Improvement in Steam-Generators; and we do hereby declare that the following is a full, clear, and exact description thereof, which will enable those skilled in the art to make and use the same, reference being had to the accompanying drawings forming part of this specification.

This invention relates to a new and improved construction of boilers for the generation of steam, whereby the steam-generating surface is greatly increased; and it consists, firstly, in the peculiar construction of the fire-box and combustion-chamber, and secondly, in the manner in which atmospheric air is introduced into the fire-box, as we will proceed to describe.

Figure 1 represents a vertical central section of the generator, it being through the line $z z$ of fig. 2, showing the fire-box and the air-tube through which air is admitted into the furnace.

Figure 2 is a horizontal section through the line $y y$ of fig. 1.

Similar letters of reference indicate corresponding parts.

This generator is formed of an outer and an inner shell, surrounded by a jacket.

The flue for the ascent of the smoke and products of combustion is between the jacket and the outer shell.

A represents the jacket, B the outer shell, C the inner shell. D is the furnace or fire-box, E is a combustion-chamber, and F is the air-tube. G indicates the grate.

It will be seen from the drawing that the fire-box is cone-shaped, and that the products of combustion pass through the water-space in diving-flues, marked J, and from them into the ascending flue H, as indicated by the arrows. The combustion-chamber E is placed above the top of the flues J, which flues are connected to an offset in the inner shell, which may be considered the dividing line between the combustion-chamber and the fire-box, as seen in the drawing.

The most important feature of our invention is the introduction of a current of atmospheric air through the grate and fuel into the midst of the fire by the pipe or tube F. To produce perfect combustion in a furnace, it is well known that a certain quantity of air (or oxygen) is required, and that in most cases, and in fact in all cases where the air to supply the combustion is introduced in the ordinary manner, that supply is very deficient, and the consequence is imperfect combustion and waste of fuel. The quantity of air which we thus introduce into the furnace, and by which we remedy the evils of imperfect combustion, is regulated by a valve seen at a, and the current of air through the tube F may impinge against a plate, F', placed over the end of the air-pipe, as seen in the drawing, and discharge the air in a thin horizontal sheet, flowing in every direction from the plate F', or it may be discharged through small apertures, in jets from a pipe or funnel-shaped head, as may be deemed most advisable.

The outside shell and jacket may be either conical in shape, or formed with parallel sides, as may be most convenient. c indicates stays for strengthening the boiler. K indicates the steam-space, which, it will be seen, is surrounded by the heated products of combustion. L indicates the door or aperture for the introduction of fuel.

It will be seen that by this arrangement and construction of fire-box we not only get a very broad grate-surface for our fuel, but a very extensive steam-generating or fire-surface in our boiler, and with the increased combustion of the fuel which we produce by our method of supplying the fire with oxygen, we feel confident that we furnish to the public what is so much needed, a safe and most economical steam-generator.

Having thus described our invention, we claim as new, and desire to secure by Letters Patent—

The steam-generator, constructed as described, consisting of the conical furnace D, having the air-tube F, and supporting the conical combustion-chamber E, the points of their connection forming shoulders, connected by the diving-flues J with the casing B, enclosing the water-space, and placed concentrically within the outer casing A, the space between said casings forming the ascending flue H, all arranged and operating as herein shown and described.

EDWIN CHAPMAN,
CHARLES T. ALLAIRE.
